UNITED STATES PATENT OFFICE.

NORMAN W. CUMMINS, OF BRIDGEPORT, CONNECTICUT, ASSIGNOR TO THE BURNS & BASSICK COMPANY, OF BRIDGEPORT, CONNECTICUT, A CORPORATION OF CONNECTICUT.

FASTENING DEVICE FOR AUTO-HOODS.

1,148,290.

Specification of Letters Patent. Patented July 27, 1915.

Application filed May 24, 1915. Serial No. 30,027.

To all whom it may concern:

Be it known that I, NORMAN W. CUMMINS, a citizen of the United States, residing at the city of Bridgeport, county of 5 Fairfield, State of Connecticut, have invented certain new and useful Improvements in Fastening Devices for Auto-Hoods; and I do declare the following to be a full, clear, and exact description of the invention, such 10 as will enable others skilled in the art to which it appertains to make and use the same.

My invention relates to fastening devices for automobile hoods, and has for its object to provide a fastening device especially adapted for use in connection with an automobile hood where it is desired to detachably secure the same in closed position.

A further object of my improvement is to 20 provide such a fastening device as will permit the sliding movements of the hood and at the same time preserve the closed position of the latter.

With these ends in view my invention 25 consists in certain details of construction and combination of parts hereinafter described and then particularly pointed out in the appended claim.

In the accompanying drawing Figure 1 30 is a sectional view partly in elevation of the approved form of my improvement. Figs. 2, 4, and 6, are similar views showing slightly different ways of carrying out my invention. Fig. 3 is a section at the line 35 3—3 of Fig. 2, and Fig. 5 is a section at the line 5, 5 of Fig. 4.

Similar numerals of reference denote like parts in the several figures of the drawing.

Heretofore devices of this description 40 have been constructed in which a hollow member was employed in connection with an interiorly headed rod which was surrounded by a coil spring that was confined between the hollow member and the head 45 of the rod, the member that engaged the automobile hood being in some instances secured to the hollow member and in others to the rod itself.

My improvement does away with the rod 50 element in that I employ two telescoping slidable hollow members with a spring contained within the innermost member, the ends of the spring being suitably secured so as to render the sliding movements be- 55 tween the members resilient, and the mem-

ber that engages the automobile hood is secured to either one of the slidable members.

Referring to Fig. 1, 1 is a tubular member formed at its lower end into a partially rounded or ball shaped portion 2 which contacts with a socket member 3 to form a swivel mounting, the member 3 being secured in any suitable manner to a fixed support. 4 is likewise a tubular member slidably arranged 60 outside the member 1, and to the upper portion of this member 4 is secured a hand lift 5 which is formed with a handle portion 6 and a hook portion 7, the latter adapted to be engaged with an engageable member 8 65 secured to the hood 9.

10 is a coil spring contained within the member 1 and whose extremities are secured respectively to the bottom portion of the lift 5, which portion is fastened to the upper part of the member 4, and to a headed pin 11 confined within the portion 2.

Still referring to Fig. 1, the device is shown engaged with the member 8 to lock the hood in closed position, and when the member 5 is lifted, the spring 10 will distend and the member 4 will slide upwardly along the member 1, and after the fastening elements have become disengaged the spring 70 will return the parts to normal position.

In the construction shown at Fig. 2 there are two elongated diametrically opposite slots 12 cut within the wall of the member 1, and a pin 13 extends diametrically through the member 4 at its bottom and 80 passes loosely through these slots, and the upper portion of the member 1 has a shouldered part 14, a spring 15 being confined between this shouldered portion and the pin 13, so that when the lift 5 is raised, this 85 spring will be compressed, while its distension will restore the parts to normal positions.

A still further modification of my improvement is shown at Fig. 4, where I have 90 dispensed with the pin 11 by lancing out tongues 16 from the body of the member 1 and folding these tongues inwardly in superposed position, and to these tongues the lower end of the spring 10 is secured, the 95 construction in all other respects being precisely like that shown at Fig. 1.

In the construction shown at Figs. 1, 2, and 4, the hand lift which, for all practical purposes, is an integral part of one of the 100

slidable members, is secured to the outer member, but at Fig. 6 I have shown this arrangement reversed, an outer tubular member 17 being formed at its lower end 5 into a partially rounded or ball shaped portion 18 which coacts with the socket 3 in the manner above specified, and a tube 19 is slidably arranged within the tube 17, the lift 5 being connected directly to this tube 10 19, while the spring 10 has its ends secured to the lower portion of the lift and to the headed pin 11 in the manner above specified, the operation of this construction being precisely the same as that shown at Fig. 1. 15 It will therefore be clear that it is immaterial as to which one of the slideable tubular elements is connected to the hand lift, and I therefore do not wish to be limited in this respect.

Having thus described my invention what 20 I claim as new and desire to secure by Letters Patent is:—

In a device of the character described, a socket member, two hollow tubular members and slidably telescoping one within the 25 other, one of the tubular members having one end formed with a rounded portion for engaging in the socket member, a hand lift secured to the opposite end of the companion tubular member and adapted to prevent dislodgment of the first tubular member, the hand lift having a handle portion and a hook element, and a resilient element normally acting to contract the tubular members. 30 35

In testimony whereof I affix my signature.

NORMAN W. CUMMINS.
